UNITED STATES PATENT OFFICE.

JOSEPH TEMPERLEY, OF HOVE, ENGLAND.

CONCRETE AND LIKE MIXER.

Application filed June 6, 1925. Serial No. 35,466.

This invention relates to mixers for mixing concrete, tar macadam and other road-making materials, and the like.

More particularly the invention relates to mixers of the tilting drum type which are adapted to be rotated for mixing purposes on an axis inclined to the vertical and having internal vanes whereby the mixing of the material is effected.

10 An object of the invention is to provide an improved arrangement of the vanes in a mixer of the type set forth whereby an improved mixing of the material is effected.

According to the invention vanes are provided which rise from or commence at the bottom of the drum and are extended upwardly in a helical or other suitable path around the wall of the drum, whereby the material at the bottom of the drum is adapted to be lifted by the vane, carried up to a substantial height and then thrown again to the bottom of the drum.

The number of the vanes may vary according to the size of the drum. Thus two vanes may be provided rising from the bottom at 180° apart. Three or more equally spaced vanes may, however, be arranged.

The accompanying drawings illustrate the application of the invention to two forms 20 of mixers,

Figures 1 and 2 being a sectional elevation and plan respectively showing diagrammatically one form of drum with the improved arrangement of vanes,

Figures 3 and 4 being similar views with the invention applied to the well known "Jaeger" mixer.

Mixing drums of the tilting type may be considered to comprise an upper frusto-conical part 5 terminating in the charging and discharging mouth 6, a central cylindrical part 7, and a lower closed or dished part 8 which is provided with a curved wall 9 merging into the cylindrical part. When 40 in the tilted mixing position the curved wall occupies the lowest position, the material falling to such part as the drum is rotated. For the purposes of this description this curved part will be considered and referred 45 to as the bottom of the drum.

In carrying out the invention according to the arrangement shown in Figures 1 and

2, the drum is provided with a pair of solid helically arranged internal vanes 10 which rise from the bottom of the drum at 180° apart and extend upwardly a suitable distance, e. g. to about two-thirds the height of the drum and each around at least one-third of the circumference of the drum; as shown the vanes 10 extend 180°. The vanes at 55 their bottom end 11 extend substantially radially and may be of such width that the centre of the drum is blocked.

Conveniently this may be effected by utilizing a drum which has an inwardly extending conical or like part 12 by which it is mounted on its support for rotation. By extending the vanes 10 to such conical bearing portion by means of the extension 13, or by blocking the centre in any other suitable manner, the whole of the material which collects at the bottom will be lifted by each vane in turn. At their lower ends the vanes may be connected to a common partition extending across the drum.

The vanes 10 may decrease in width gradually as they extend upwardly as shown in Figure 2 and may terminate abruptly or be merged into the casing if desired, or they may be of constant width throughout their 70 length.

The surfaces of the vanes may be twisted or of varying pitch if desired, or the pitch may be constant.

The inner edges 14 of the vanes may be 85 curved upwardly for a portion of their length and preferably near their lower ends so as to prevent spilling of the material until the latter has been raised the desired height.

Adjacent the upper end of the vanes secondary vanes may be provided which are opposed in direction to or extend across the path of the helical vanes and against which the material or a part thereof may be thrown to improve the mixing. Such secondary vanes may comprise two or more slats spaced from one another and from the surface of the drum, being supported by suitable brackets.

In applying the invention to a mixing drum of the "Jaeger" type (see British Patent No. 148,076) in which a pair of flats 15 are provided on opposite points of the

dished part of the drum, see Figures 3 and 4, the lower ends of the vanes may form a continuation of such flats or be positioned adjacent thereto whereby the material after being acted upon by such flats is then caught up by the vane and carried upwardly the desired distance.

Figures 3 and 4 also show an arrangement of secondary vanes comprising spaced slats 16 fixed to the drum by brackets 17. The material caught up by the vanes 10 is adapted to be thrown onto the slats 16.

Although the vanes 10 have been described as solid they may be partly solid and partly 15 perforated or open, thus the lower parts adjacent the bottom of the drum may be solid while the upper portions may be formed of slats. Further the upper surfaces of the vanes may be corrugated or provided with 20 radial ribs to increase the turning over and mixing of the material.

The vanes may be mounted upon the drum in any convenient manner as by the provision of a suitable number of brackets similar to 25 those indicated at 17.

Although the invention has been described in connection with a mixer having a wall comprising a surface of revolution it may be applied to drums which are other than 30 circular in cross-section.

Having now described my invention, what

I claim as new and desire to secure by Letters Patent is:—

1. A mixer of the type adapted to rotate about an inclined axis during the mixing operation, comprising a drum having a frustoconical upper wall part provided with a charging and discharging mouth, and a dished lower part connected to the frustoconical part and forming a closed bottom 35 wall of the drum, and vanes connected to the inner wall of the drum and extending spirally upwardly from the bottom of the drum, the lower ends of the vanes extending inwardly to the axis of the drum for forming a partition across the bottom of the drum. 40

2. A mixer as claimed in claim 1 wherein the dished lower part is provided with a re-entrant axial hollow portion forming a bearing adapted to receive the shaft in which the drum rotates, the lower ends of the vanes extending inwardly to such re-entrant part. 45

3. A mixer as claimed in claim 1 in which the dished part of the drum is provided with flat portions alternating with parts conforming to a surface of revolution. 50

In testimony whereof I have signed my name to this specification.

JOSEPH TEMPERLEY.
